COMBINATION CIGARETTE SUPPORTING
AND EXTINGUISHING DEVICE

Harry L. Bachman, Sr., Columbus, Ohio

Application November 22, 1950, Serial No. 197,095

1 Claim. (Cl. 131—256)

1

The present invention relates generally to smokers' articles, and more specifically to an improved combination cigarette holder or supporting tray and an extinguishing device.

In the past, numerous types of devices have been proposed for use in supporting and extinguishing lighted cigarettes, cigars, and the like to prevent continued burning of the cigarette or cigar, and the possibility of the same dropping from an ash tray or other support onto a table surface or floor with consequent fire hazards. However, previously known devices of this type generally comprised a tubular socket into which the lighted end of a cigarette was inserted to smother the fire and thereby extinguish the cigarette upon the insertion thereof within the device. Such devices were entirely sufficient for the purpose of extinguishing a lighted cigarette, but in all constructions of which I am aware, the burning end of the cigarette, prior to extinction, was permitted to smolder with consequent condensation of acid tars upon the paper of the cigarette adjacent the burning end thereof. It will be manifest that such condensation occurring from the enclosure of the burning end of the cigarette rendered the cigarette worthless for reuse due to the bitter taste imparted by the acid tars collecting in the paper and at the burned end of the cigarette. For this reason, extinguishers which function to snub or smother the fired end of the cigarette function merely as an extinguisher only, and substantially preclude reuse of the cigarette after extinguishment.

It follows, therefore, that the primary object of the present invention is to provide a cigarette supporting tray and extinguisher into which a lighted cigarette may be inserted or laid at rest, and which functions to maintain combustion of the cigarette for a relatively short period of time, permitting the cigarette to be removed from the tray within a short interval from the time it is initially positioned therein without requiring the same to be relit, but which functions to finally extinguish a burning cigarette after prolonged insertion within the tray without causing condensation of acid tars on that portion of the cigarette adjacent the burning end thereof.

Another object of the invention is to provide a combined cigarette holding tray and extinguishing device which functions to maintain the portion adjacent the lighted end thereof in spaced relation to the inner walls of a tubular chamber which functions to eventually smother the cigarette without causing an accumulation of moisture or condensates upon the paper body of the cigarette.

2

A further object of the invention is to provide a cigarette support having means to extinguish the cigarette if left upon the support for a predetermined time, but which additionally is provided with a means to maintain combustion of the cigarette for a relatively short period of time to enable the smoker to initially position the cigarette upon the tray and thereafter remove the same at normal intervals to continue smoking, while at the same time eliminating the fear that the cigarette will continue to burn and perhaps drop from the tray to cause a fire hazard.

For a further and more detailed understanding of the present invention, and the various additional objects and advantages realized therefrom, reference is made to the following description and the accompanying drawing, wherein:

Fig. 1 is a medial longitudinal vertical sectional view taken through a combined cigarette holder and extinguishing device formed in accordance with the present invention;

Fig. 2 is a top plan view thereof;

Fig. 3 is a transverse vertical sectional view taken along the line 3—3 of Fig. 1;

Fig. 4 is a detailed fragmentary vertical sectional view taken through a slightly modified form of cigarette holder and extinguishing device;

Fig. 5 is a perspective view of the holder and extinguisher disclosed in Fig. 1; and

Fig. 6 is a transverse vertical sectional view taken through my improved cigarette holder and extinguisher and showing a removable moisture-adsorbent sleeve arranged to collect condensates.

In accordance with the present invention, I have found that by inserting the lighted end of a cigarette within a cylindrical tubular sleeve having an internal diameter slightly larger than the outer diameter of the cigarette, and also having a relatively narrow longitudinal slot formed therein, the cigarette will continue to burn for a relatively short period of time, say in the neighborhood of one minute, without being immediately extinguished. Also, due to the relative spacing between the outer surface of the lighted end portion of the cigarette and the inner wall of the tubular sleeve, vapors given off from the cigarette due to the heat occasioned by the burning end thereof are dissipated from the tubular sleeve or condense upon the inner side walls thereof rather than upon the outer surface or paper of the cigarette. Hence, as the cigarette extinguishing progresses, the previously burnt end thereof is free from an accumulation of tar and/or acid condensates, thereby permitting relighting and resmoking of the remaining unburnt portion of the cigarette.

Another object of the invention is to provide a combined cigarette holding tray and extinguishing device which functions to maintain the portion adjacent the lighted end thereof in spaced relation to the inner walls of a tubular chamber which functions to eventually smother the cigarette without causing an accumulation of moisture or condensates upon the paper body of the cigarette.

Referring now to the drawing, and particularly to the form of the invention disclosed in Figs. 1-3, the numeral 10 designates generally a flat supporting base from which arises an arcuate supporting bracket 11. Carried upon the upper arms of the bracket 11 is an elongated tray member 12 which is formed to provide a relatively shallow arcuate cross-sectional configuration for the support of the body portion of a cigaret indicated at 13. Secured to one end of the tray member 12, by any suitable means, such as welding or soldering, is a cylindrical tubular sleeve 14 whose internal diameter is slightly larger than the external diameter of the cigaret 13. The outer end portion of the tray member 12 extends slightly within the sleeve 14, as at 15, to provide a raised support with reference to the lower portion of the sleeve 14 for the burning end of the cigaret 13.

The tubular sleeve member 14 is formed in its lower region with a longitudinally extending open slot 16 which functions to admit air radially into the tubular sleeve sufficient to sustain combustion of the cigaret for a relatively short period of time, and to prevent immediate extinguishment thereof upon insertion within the sleeve. The size of the slot 16 may be preselected to vary within limits the burning time of the cigaret after insertion within the sleeve, but is of an insufficient width to furnish sufficient air to sustain prolonged and rapid combustion of the tobacco products comprising the cigaret. In this connection, it is important to note that after initial insertion of the burning end of the cigaret within the tubular sleeve 14, the same will, depending upon the size of the slot 16, remain lighted for a period of from thirty to ninety seconds, but substantially no smoke will emanate from the cigaret after insertion within the sleeve. This phenomenon is explained on the theory that the burning of the cigaret is progressively decreased due to the insufficiency of combustion air passing into the tubular sleeve, and hence substantially no smoking is encountered.

Due to the radially offset relation of the outer end of the tray member 12 with respect to the lower surface of the sleeve 14, and also due to the difference in diameter of the sleeve and the cigaret, the outer surface of the burning end of the cigaret will remain in spaced relation to the inner wall of the sleeve 14 to thus prevent the condensation of vapors comprising acid tars upon the cigaret wrapper. If the cigaret 13 is permitted to remain within the sleeve 14 for a period of time sufficient to effect extinguishment, the same may thereafter be removed from the sleeve and tray and relit so that the remaining unburned portion of the cigaret may be consumed. It will be manifest that the prevention of condensates accumulating upon the outer surface of the burned end of the cigaret enables the same to be reused without encountering the distasteful effects normally occasioned by such condensates. If the burning end portion of a cigaret were permitted to lie against the inner surface of the sleeve 14, as with prior constructions, undesired moisture and condensates would immediately accumulate upon the outer surface of the cigaret, rendering the same unsuitable for reuse.

I have further found that it is advantageous to provide a removable liner sleeve 17 formed from a suitable moisture-adsorbent fibrous material, and arranged to be removably inserted within the sleeve 14 adjacent to the inner wall thereof,

yet in spaced relation to the outer surface of the cigaret. In this manner, vapor condensates and tar deposits are collected upon the disposable sleeve 17 and prevented from accumulating upon the inner wall of the permanent sleeve 14. Thus, by removing and replacing the sleeve 17, the device may be maintained in a clean and sanitary condition without resorting to reaming of the outer sleeve 14.

Fig. 4 of the drawing discloses a slightly modified construction wherein the tray member 12 and the sleeve member 14 are of integral construction, with the inner end of the sleeve portion 14 formed with a restricted shoulder or collar 18 which functions to hold the burning end portion of a cigaret in spaced relation to the inner walls of the sleeve member 14. The relative spacing between the outer diameter of the cigaret 13 and the inner wall of the sleeve 14 is maintained in this modified form by the offset relation of the collar 18 with respect to the remainder of the sleeve 14.

While the device has been described as a self-supporting unit, it will be manifest that the same may be mounted in association with an ash tray without departing from the spirit of the invention.

In view of the foregoing, it will be seen that the present invention provides a useful and mechanically efficient device for supporting burning cigarettes in a manner to prevent the accumulation of undesired condensates thereon, thus permitting reuse of the unburned portion of the cigaret after extinguishment thereof. Further, the device provides an extinguisher which assures against continued burning of the cigaret, yet permits burning thereof for a predetermined relatively short interval of time commensurate with the interval of actual smoking by the person. Further, the present combined holder and extinguisher prevents the undesired smoking of the cigaret when placed therein prior to extinguishment, thus reducing the amount of smoke and eliminating entirely the undesired smoldering of the cigaret as normally occasioned when the same is placed within an ordinary ash tray.

I claim:

A cigaret-supporting and extinguishing device, comprising an elongated substantially horizontally disposed tray having a shallow trough adapted to receive a burning cigaret; and a tubular sleeve carried rigidly at one end of said tray, said sleeve being formed with a bore extending therethrough and into which the burning end of a cigaret positioned in the trough of said tray may be inserted, said sleeve being formed with a longitudinally extending open slot through which air may pass radially inwardly of the sleeve, said slot extending linearly of the sleeve from the end of the trough, with the slot located in the lowest portion of the sleeve in order to provide necessary draft for maintaining for a limited period of time combustion of the burning end of the cigaret following insertion thereof into said sleeve, said sleeve having a diameter slightly larger than the diameter of the cigaret, the wall of said sleeve being disposed in partial overlapping and radially offset relation to the trough of said tray, whereby the burning end portion of a cigaret positioned in the bore will be maintained in spaced relation to the wall thereof.

HARRY L. BACHMAN, SR.
